J. MORRIS,
LADY'S HAT FASTENING,
APPLICATION FILED DEC. 18, 1913.

1,144,561.

Patented June 29, 1915.

UNITED STATES PATENT OFFICE.

JACOB MORRIS, OF SYDNEY, NEW SOUTH WALES, AUSTRALIA.

LADY'S HAT-FASTENING.

1,144,561.

Specification of Letters Patent. Patented June 29, 1915.

Application filed December 18, 1913. Serial No. 807,497.

To all whom it may concern:

Be it known that I, JACOB MORRIS, of 61 Oxford street, Sydney, in the State of New South Wales, Commonwealth of Australia, 5 manufacturer, have invented certain new and useful Improvements in Ladies' Hat-Fastenings, of which the following is a specification.

This invention relates to improvements in 10 ladies' hat fastenings and has for its object the provision of an exceedingly efficient device which is simple, durable, light and capable of ready attachment to the inside of a hat-crown.

15 The disadvantages incident to the use of the ordinary hat-pins are their liability to work loose and fall out when the hat is worn in the wind or when used with a hat made of a material which does not furnish a good 20 frictional grip on the pin. Moreover, when the pins work loose the hat is liable to assume an angle which is by no means becoming to or desired by the wearer, and, furthermore, their construction necessitates 25 careful handling to prevent accidental injury to the wearers themselves or to others near by. Furthermore, the use of pins seriously damages the hat and its trimmings, which disadvantage the present invention 30 entirely obviates as the fastening is located within the crown.

Now the present invention is thoroughly reliable in its action and possesses none of the above-mentioned disadvantages and it 35 will permit of a hat being easily and quickly placed on the head of a wearer and removed therefrom without disarranging her coiffure.

The invention broadly consists of a wire 40 hoop or ring which is fitted neatly in the crown of a hat and provides a support for a torsional spring having an arm or loop to which is fitted pivotally a straight or suitably curved comb. The comb is so arranged 45 that it will grip the arm or loop firmly when in its normal position and remain fixed until actuated by the wearer.

Locking members of special construction and design are used in combination with the comb to prevent the latter and consequently 50 the hat being accidentally displaced.

The invention is illustrated in the accompanying sheet of explanatory drawings wherein:—

Figure 1 is a view in perspective of one 55 form of the fastening. Fig. 2 is a similar

view showing a slight modification in the construction of part of the fastening. Figs. 3 to 8 are views of constructional details of the fastening. Figs. 9 to 12 are views in perspective of further modifications in the 60 construction of parts of the fastening. Fig. 13 is a view similar to Figs. 1 and 2 and illustrates a modified form of fastening.

In these drawings the letter *a* designates a ring or hoop of wire or other material 65 shaped to fit within the crown of a hat *a'* and be secured therein by stitching, by clips or other convenient means (not shown). The said ring *a* is provided on top with a torsional spring *b* which is made by fixing a 70 piece of wire to the ring *a* by the use of S-shaped clamping pieces *c*, the said wire passing through the upper tubular members and the ring *a* through the lower tubes of the same, the spring *b* being in a plane parallel 75 to the plane of the ring *a* throughout a large portion of the circumference of the ring *a*.

The torsional spring *b* may be made of one 80 piece of wire having its ends bent upwardly and suitably connected.

The ends of the wire forming the ring *a* can be coupled fixedly by means of one of the said clamping devices *c* or they can be adjustably connected by a clamping device *c'* see Fig. 8. The clamping device *c'* grips 85 the overlapping ends of the wire *a* sufficiently tight to retain the ring in any particular size to suit the crown of a hat to which it is to be fitted.

If preferred, the ring *a* can be made of a 90 wavy outline as shown in Fig. 2 of the drawings and when made in this way it provides a better support for the rim or crown of the hat. By forming the ring *a* in the above mentioned manner it can be 95 made to assume any desired angle by opening or closing the loops or curves as desired.

A portion of the wire *b* is bent upwardly 100 at a suitable point to form a rectangularly shaped loop *e* having its central portion strengthened by a tubular or other covering *d* formed integrally with a locking member *d'* for retaining the hat fastening means in a desired position within the hat *a'* in opposition to the diverse strains applied to the 105 same when worn in the wind. The ends of the torsional spring *b* are inserted and retained in the tubular or rolled portion of the locking member *d'* in a suitable way.

The wire to form the torsional spring *b* 110

which is of good quality steel, is made with an upwardly and inwardly bent arm *f* formed integrally by looping up the wire at that point directly opposite the locking member *d*¹ and to the upper end of said arm is pivotally fitted the said fastening member.

The fastening member is constructed of two or more pieces of wire *g* and *h*, shaped into the form of a comb which is connected to the looped arm *f* in such a way that one or two of the inner members thereof will have a spring or frictional grip on said arm *f* when in its normal or locked position.

15 The central or upper part of the looped arm *f* is made straight and provides a pivotal support for a plate *i* of special construction having its inner end formed into a tubular bearing *j* through which the top 20 of the looped arm *f* passes to effect a pivotal connection with the fastening comb. Said plate, furthermore, has its two side portions formed into tubular bearings *k* and *l* through which the wires *g* and *h* respectively are passed and extended to form the teeth of the fastening comb.

The plate *i* and manner of the connection thereto of the wires *g* and *h* are essential constructional features of my invention. 30 The inner ends of the teeth of the comb, or the two inner teeth when more than two are employed, are bent upwardly at *m* and inwardly at *n* so that when in their raised and normal positions the inbent portions *n* 35 will be above and bear against the upper end of the looped arm *f* and so insure the comb being retained in correct position relatively with the said looped arm.

A looped finger piece *o* is connected pivotally to a bearing *p* on the outer end of the plate *i* and provides a convenient means of operating the fastening and said loop can be varied in construction and design to suit different tastes or styles of hats.

45 The plate *i* is cut from flat sheet metal into the form shown in Fig. 3 of the drawings and the lug portions *q* shown thereon are rolled over to form the bearings *j*, *k*, *l* and *p* before described.

50 The locking member *d*¹ preferably used for the outer end of the comb is that illustrated in Figs. 1, 2, 5 to 8 of the drawings. This locking member *d*¹ is slightly arched and is of V-shaped formation in 55 cross section with one of its sides inclining inwardly beneath the outer end of the comb while the opposite side forms the top and has an inclination corresponding to and serves to limit the upward movement of the

60 points of the comb. This locking member *d*¹ is arranged so that when the hat is placed on the head and the comb slid through the wearer's hair the outer ends of said comb rest thereunder. The corresponding side of the hat is then depressed

which causes the said locking member *d*¹ to move slightly outwardly when the end of the comb immediately slips into the V-shaped cavity formed by the inclined sides of the locking member. The torsional 70 spring causes the said member to resume its normal position thereby automatically effecting a locking of the outer end of the comb with a clicking sound while the opposite or inner end of said comb has been previously locked by forming a frictional or 75 spring engagement with the said looped arm *f*. By this means a double and automatic locking engagement is effected at both ends of said comb in an expeditious manner and 80 practically at the same moment.

The arm *f* and wires of the loop *e* are so arranged that the points of the comb teeth are pressed into the angle of the locking member when the fastening is in its normal 85 position.

The inwardly inclined side of the locking member is pivotally connected to the top by 90 hinges *s* and normally is retained in its correct relative position with the top by means of a spring or springs *t*. The spring *t* can be made in the form of a coil as shown in Fig. 9 or one or more flat springs *u* can be used as shown in Figs. 10 and 11.

When a coil spring *t* is used it is mounted 95 on the hinge pin *v* and one end of the spring is arranged to bear on the top and the other end on the inclined side of the locking member.

When employing a flat spring it has one 100 end secured by rivets or screws to the top of the locking member and the opposite end of the spring is arranged to bear on an outwardly projecting part *w* of the inwardly inclined side.

In both of the constructions above described the collapsible or inwardly projecting part of the locking member normally is made to bear against an abutment member or members *x* by the pressure of the springs. 110

The locking member *d*¹ and the comb can be molded or stamped out of metal, vulcanite, papier-mâché or other similar material and can be connected directly to the upper end of the loop *e* and arm *f*, respectively, in an approved way.

In lieu of employing a locking member *d*¹ as before described the central part of the loop *e* can be furnished with a piece of tubing *r* as shown in Fig. 13, which tubing 120 serves to strengthen the loop and to connect the ends of the wire forming the same.

The head-lining can be sewn or otherwise secured to the ring or hoop *a* and inserted into the crown of the hat together with the 125 fastening means.

The wire forming the loop *e* and arm *f* is set to insure the comb and locking member being lifted and kept away from the scalp.

To affix a hat fitted with that form of the 130

invention shown in Figs. 1 and 2 of the drawings the wearer pulls the comb out of the crown of the hat and grasps the plate *i* or base of the comb between the finger 5 and thumb. The comb is then in the position shown in dotted lines in Fig. 1 and when thrust sidewise through the hair it is released and the spring arm *f* carries it into the crown of the hat and incidentally pulls 10 the hat down upon the head.

When the comb passes into the crown and the hat is drawn down on the head the inner end of the comb engages the arm *f* or if it does not do so by the upward pressure 15 of the arm a slight downward pressure can be put on that particular side of the hat and they will then readily engage each other. The points of the comb now lie beneath the downwardly inclined portion of 20 the locking member *d*¹ and to make the points of the comb enter the same that particular side of the hat is pulled or pressed downwardly until the wearer hears the "click" or slight sound caused by the comb 25 teeth springing into their locked positions.

To remove the hat the wearer with a finger holds the loop of the finger piece *o* and with the remaining fingers of the same hand presses upwardly on the underside of the 30 ring *a* or adjacent part of the hat crown. These opposing pressures cause the inner ends of the comb teeth to be disengaged from the arm *f* and the hat to be raised at the side thereby permitting the comb to be 35 slid outwardly until free of the hair.

Directly the points of the comb are clear of the locking member *d*¹ that side of the hat can be raised to prevent it touching the hair when the hat is passed over the head 40 to permit of the comb being moved clear of the hair.

The comb, arm and locking member are curved or shaped so that when in their normal positions they will lie well within the 45 crown of the hat and thereby insure every comfort for the head of the wearer while an additional feature is that the fastening is so constructed and the parts thereof arranged that it may be secured to or be removed from a hat in one piece.

To remove a hat having a fastening furnished with a locking member having a collapsible side as illustrated in Figs. 9 to 12 all that is necessary to release the points of the 55 comb therefrom is to press upwardly on the side of the crown below the said member.

The upward pressure causes the inwardly inclined side of the said locking member to be forced outwardly—as shown in Fig. 11—60 thereby permitting it to be moved upwardly past the points of the comb.

The strength of the spring or springs must not be sufficient to cause an undue pressure or strain on the hair nor weak enough 65 to permit of the comb becoming disengaged

from the locking member when the hat is worn in the wind.

When the comb has moved out of engagement with the locking member the collapsible side thereof is returned immediately to 70 its normal position and the hat can be raised sufficiently high to permit of it being slid sidewise to remove the comb from the hair.

When the locking member is constructed as above described the finger-piece *o* can be 75 dispensed with or made much shorter and used only when pulling the comb out of the crown preparatory to placing the hat upon the head of the wearer.

To affix a hat fitted with that form of the 80 invention shown in Fig. 13 on the head, the wearer grasps with the finger either the finger piece *o*, the inner ends of the teeth of the comb, or the upper end of the arm *f*—using the loop of the finger piece *o* as a leverage—85 and pulls downwardly. This action unlocks the teeth from their engagement with the upper end of the looped arm *f* and causes the latter to swing downwardly and carry the comb clear of the crown (as shown by 90 the dotted lines).

The locking member *r* is pulled downwardly out of the hat crown and when the hat has been placed in a correct position by 95 passing the comb laterally across the head of the wearer the said comb is released and the torsional strain on the wire *b* will draw the arm *f* and comb into the crown and consequently the hat downwardly to the head 100 of the wearer.

Two of the wires of the comb are bent inwardly toward each other as indicated at *n* so as to have a less distance between them than that of the width of the loop *f*. Consequently when the parts are pressed upwardly into the hat the loop *f* springs these wires apart in order to arrive at the position shown in full lines in Fig. 13. The comb is thus interlocked with the loop *f* because the inner wires of the comb now overlap and press against the sides of the loop sufficiently tight for the usual situation. The part *n* of the wires of the comb thus being in front of the loop *f* as regards the direction of stress given the loop by the spring *b*, the loop 110 presses against the part *n* so as to hold the comb firmly in place, so far as one end thereof is concerned. The other end of the comb is held and supported by the member *r*. 115

When the comb has been thrust through 120 the hair the locking member *r* is released and passes or is passed upwardly into the crown of the hat so as to be beneath the ends of the comb teeth. The locking member will prevent the hat being accidentally lifted at the 125 sides or displaced unless an unusual amount of force is applied thereto. The hat now can be adjusted easily to a desired position by the wearer without inconvenience or disarranging the hair in the slightest. 130

To remove the hat, the wearer grips the finger piece *o* or inserts the fingers into the crown to grip the arm or comb which is then pulled downwardly and outwardly until it is clear of the locking member *r* when that side of the hat is raised and then moved or slid across the top of the head to take the comb out of the hair and remove the hat.

What I do claim is:—

- 10 1. A lady's hat fastening comprising an arm, a comb pivoted to and normally having a frictional engagement therewith, a spring adapted to control said arm, and a locking device engaging the points of said comb 15 when in its normal position within the crown of the hat.

Copies of this patent may be obtained for five cents each, by addressing the "Commissioner of Patents, Washington, D. C."

2. A lady's hat fastening comprising a curved torsional spring, a ring to which said spring is fitted, said ring adapted to be secured within the crown of a hat, a depressible arm on said spring, a comb pivoted to and normally having a frictional engagement with said arm, and a locking device on the opposite side of the spring, normally covering the points of the comb, substantially as described.

In testimony whereof I affix my signature in presence of two witnesses.

JACOB MORRIS.
